REVERSE ANGLE INTERLOCK PILING

Adolf Borberg, Short Hills, N. J., assignor to
Dortmund Hoerder Huettentechnik Aktiengesellschaft, Dortmund, Germany, a corporation of
Germany

Application January 5, 1934, Serial No. 705,361

4 Claims. (Cl. 61—62)

This invention relates to sheet metal piling of the interlock type, and has for its object to provide a new section profile which adapts the section to useful employment in a greater variety of positions. By the use of the profile herein shown and described, the same section may be used for the construction of a straight wall or a curved or angular wall, depending upon the manner of assembling the adjacent sections.

10 In principle, the construction according to the present invention involves the use of reversed single or double-acting interlock edges in which the interlock axis of one edge is in angular relation to the interlock axis of the other edge. This principle may be embodied in various types of reverse interlock construction, and the angular relation of the two interlock axes of a section may be attained by forming the axis of either one or both of the interlocks at an angle to the section axis. I prefer, however, to form each of the interlock axes at an angle to the section axis. The invention is furthermore applicable to either straight web or arched or deep arched web sections.

25 To clearly illustrate the principles of the invention, I have shown in the accompanying drawings several examples of constructions embodying the invention.

In said drawings—

30 Figure 1 is a cross-section of a straight web section having the interlock axes at the two edges disposed at an angle to each other and at an angle to the pile axis.

35 Figure 2 is a similar view showing the assembling of the sections of Figure 1 to form a straight wall.

40 Figure 3 is a similar view showing the assembling of the sections of Figure 1 to form a curved wall.

45 Figure 4 is a similar view showing the application of the invention to an arched web section.

Figure 5 is a similar view illustrating the assembling of the sections of Figure 4 in the construction of a straight wall.

50 Figure 6 is a similar view illustrating the assembling of the sections of Figure 4 to form a curved wall.

Figure 7 is a similar view in which the angular disposition of the interlock axes is obtained by the rolling or bending of a straight web section to form an angular web.

55 Figure 8 is a similar view illustrating the assembling of sections of the type illustrated in Figure 7, to form a straight wall; and

Figure 9 is a similar view illustrating the assembling of the sections, shown in Figure 7, to form a curved wall.

60 Referring to Fig. 1 which shows a pile section with its web 10 extending closely and in parallel to the section axis 15, it will be noted that at

the right hand section edge the hook member 11 extends substantially in the direction of the section axis 15, while the guard member 12 rises from the web at a pronounced angle to this axis before it curves toward the end of the hook. Inversely at the left hand section edge the hook member 13 rises from the web at a pronounced angle to the section axis 15, while the guard member 14 extends mainly in the direction of this axis. This unlike or dissimilar positioning of the 10 component interlock members at each section edge with respect to the main section axis 15 results in this and in all modifications within the scope of this invention in the angular inclination of the two axes of interlock at the two 15 section edges with respect to one another (for instance angle γ in Fig. 1) and with respect to the main section axis, as will be noted from the inclination α of the interlock axes 16 and 17 in Fig. 1.

20 If adjacent sections thus constructed are joined at like contoured edges as shown in Fig. 2 the result is a pile wall with a straight main axis, while the joining of adjacent sections at unlike contoured edges, as shown in Fig. 3, results in 25 a pile wall with a continuously curved or continuously broken main wall axis.

20 These two entirely different results which, it should be particularly noted, can be produced with the same kind or unit of pile section, are 30 due to the fact that the aforementioned angles which the axes of interlock of two adjacent section edges form with their appertaining section axes 15, are disposed in one case alternately on opposite sides of the pile wall, thereby “neutralizing” as it were, mutually their effect upon the direction of the wall, so that a wall with a straight main axis results, as shown for instance in Fig. 2.

In this figure for instance the interlock angle α of the right hand edge of the first section 10, 40 located at the left end of the figure, is located on one side of the wall, while the interlock angle β of the similarly contoured left hand edge of the next adjoining section 10 is located on the opposite side of the wall.

45 In the other case, represented by Fig. 3, where unlike contoured section edges are joined, the interlock angles of adjacent section edges are both located on the same side of the pile wall, and are thereby added to one another, causing 50 to the extent of such angular increment added, an angular break in the main axis of the wall. Thus, for instance, the left hand interlock angle β of the middle section 10 is added to the right hand interlock angle α of the first section 10 at 55 the left hand end of the figure.

Obviously the wall of Fig. 2 may vary, if desired, to a considerable extent from a straight direction, and the curved wall of Fig. 3 may be made to curve more sharply or less sharply than 60

illustrated, because there is in all cases a certain angular displacement of the section joints permissible, without thereby unduly increasing the driving friction of the joint. But by forming 5 and placing the interlock elements at both edges of each section so that their interlock axes are inclined toward one another and form angles with respect to the section axis, a very much greater adjustment of the angular relation of the 10 adjacent sections to each other is made possible.

In Figure 4, the invention is illustrated as applied to an arched web section in which the web 20 has the short flanges 21, 22, the hook member 23 and guard 24 extending from the flange 21, 15 and the hook member 25 and the guard member 26 extending from the flange 22. Here again the interlocks are reversed, and the angular relation of their interlock axes to each other and to the section axis 15 is in this instance attained 20 by the bending of the flanges 21 and 22. Assembly of the adjacent sections with like contoured edges of adjacent sections in engagement, as illustrated in Figure 5, produces a straight wall, whereas the reversal of these connections, 25 as illustrated in Figure 6, produces a curved wall. In either case, the particular direction of the successive piles may vary also in this modification to either side to a number of degrees from the normal relation.

In Figure 7, the section is illustrated in the 30 form of a modified straight web type in which the web 30 has two axes intersecting on a line parallel to its two edges, preferably but not necessarily midway between the two edges. The hook member 31 and guard member 32 project from one edge, whereas the hook member 33 and guard member 34 project from the other edge. The positions of these two members are reversed 35 on the two edges, and the axis of one interlock or joint is at an angle to that of the other, and both axes are again, as in the previously described modifications, at an angle to the main section axis. In this modification the two shanks of the web happen to coincide with the two interlocked axes of the section, which need not necessarily be the case. For the construction of 40 a wall, having a straight main axis, with this form of pile section, the like contoured section edges are joined with each other as illustrated in Figure 8, whereas the curved main axis wall is produced by assembling the sections with their unlike contoured edges, as illustrated in Figure 9. The adjustment of the interlock a number of 45 degrees to either side of the normal, provides for considerable variation in the precise relationship 50 of the adjacent sections to each other, whether in the straight wall type of connection or in the curved wall type of connection. Also in this case it will be noted that in the straight wall form of 55 Fig. 8 as in Figs. 2 and 5, the interlock angles are located alternately on opposite wall sides, while in the curved wall form of Fig. 9, as in Figs. 3 and 6, the interlock angles are all located on the same side of the wall.

The principles of the invention are applicable 60 to either single or double-acting interlock joints of various shapes and constructions, provided they are reversed on the two edges. The pile may be straight web, arched web, or deep arched web. 65 The form of interlock and the types of pile sections shown in the accompanying drawings are therefore to be understood as being merely con-

ventional or illustrative. The particular angle at which the axis of the interlock at either side is disposed to the section axis 15 may be quite varied, so long as the two interlock axes are at an angle to each other and to the section axis 15. 5 Indeed, their angular relation may be so chosen that with the normal amount of play permitted by the joints, the wall direction in the straight wall type of connection may assume as great a degree of curvature as the lowest degree of curvature permissible with the curved wall type of connection, so that a practically continuous range of adjustment from straight to curved wall construction of maximum curvature may be attained 10 with one and the same form of profile. 15

As a further illustration of the adaptability of the one profile to various conditions, I may mention the connection of a number of the sections in the form of a straight wall, followed by a series of sections in the form of a curved wall; 20 or the formation of offsets and angles by the appropriate selection of the type of connection.

I claim:—

1. A reverse interlock pile section having unlike contoured interlock elements at its edges, and 25 in which the axis of the interlock at each edge is disposed at an angle to the section axis and to the axis of the interlock at the other edge, whereby in a plurality of interlocked sections the angles of adjacent interlock axes to their appertaining 30 section axes neutralize each other to form a straight wall when like contoured interlock edges are connected and are added to each other to form a curved wall when unlike contoured interlock edges are connected. 35

2. A straight web reverse interlock pile section having unlike contoured interlock elements at its edges, and in which the axis of the interlock at each edge is disposed at an angle to the section axis and to the axis of the interlock at 40 the other edge, whereby in a plurality of interlocked sections the angles of adjacent interlock axes to their appertaining section axes neutralize each other to form a straight wall when like contoured interlock edges are connected and are 45 added to each other to form a curved wall when unlike contoured interlock edges are connected.

3. An arched web reverse interlock pile section having unlike contoured interlock elements at its 50 edges, and in which the axis of the interlock at each edge is disposed at an angle to the section axis and to the axis of the interlock at the other edge, whereby in a plurality of interlocked sections the angles of adjacent interlock axes to their appertaining section axes neutralize each 55 other to form a straight wall when like contoured interlock edges are connected and are added to each other to form a curved wall when unlike contoured interlock edges are connected.

4. A deep arched web reverse interlock pile 60 section having unlike contoured interlock elements at its edges, and in which the axis of the interlock at each edge is disposed at an angle to the section axis and to the axis of the interlock at the other edge, whereby in a plurality of interlocked sections the angles of adjacent interlock axes to their appertaining section axes neutralize each other to form a straight wall when like contoured interlock edges are connected and are added to each other to 70 form a curved wall when unlike contoured interlock edges are connected. 75

ADOLF BORBERG.
